CUSHIONING DEVICES SUITABLE FOR USE AS RAILWAY DRAFT GEARS

Walter C. Dilg, Hewlett, N. Y., assignor to Waugh Equipment Company, New York, N. Y., a corporation of Maine

Application August 14, 1953, Serial No. 374,183

2 Claims. (Cl. 213—49)

This invention relates to cushioning devices for use primarily as draft gears in railway rolling stock and is concerned more particularly with a novel cushioning device, which is of simple construction, has no parts subject to wear, and is of high capacity and low travel. The new draft gear may be employed to especial advantage on railway freight cars for use in interchange service and an embodiment of the invention for that purpose will, accordingly, be illustrated and described in detail for purposes of explanation.

At the present time, draft gears for use on freight cars to be employed in interchange must comply with specifications prepared by the Association of American Railroads and may not be used on such cars until after having received the approval of the Association. The A. A. R. specifications provide that a draft gear must be capable of being installed in a pocket on the car, which is of stated dimensions, and the gear must have a minimum capacity of 18,000 ft.-lbs. Also, the gear must have a travel of not less than $2\frac{1}{2}$ " nor more than $2\frac{3}{4}$ " before going solid, that is, reaching a condition, in which forces are transmitted through the gear from the coupler to the car structure along an unyielding path.

The present invention is directed to the provision of a novel draft gear, which meets the A. A. R. specifications, has a substantially higher capacity than the minimum required, and can be installed in a standard yoke. In the new gear, the resilient element is rubber and the gear includes two groups of rubber springs, which are installed within respective follower assemblies of link form, each of which is made up of front and rear follower blocks connected along opposite edges by longitudinal members. The links are interconnected and, when the links with the groups of rubber springs therein are mounted within a yoke in a draft pocket, the groups of springs operate in parallel, so that the gear has the total capacity of both groups, but the travel of only one.

For a better understanding of the invention, reference may be made to the accompanying drawing, in which

Fig. 1 is a top plan view of the new draft gear installed in a draft pocket with parts of the car structure shown in section;

Fig. 2 is a view in side elevation of the draft gear installed in the yoke of a draft pocket with parts of the car structure broken away;

Figs. 3 and 4 are sectional views, respectively, on the lines 3—3 and 4—4 of Fig. 2; and

Figs. 5 and 6 are views in side elevation and plan, respectively, of the interconnected links of the new draft gear.

In the drawings, the new draft gear is illustrated as installed within a yoke and lying within a draft pocket between the longitudinal sills 10 and 11 of the car structure. The pocket is oblong in shape and wider than it is deep and it is defined at the front by a pair of stops 12 and at the rear by a pair of stops 13. The yoke is of conventional construction and includes a rear end piece 14, from which top and bottom longitudinal mem-

bers 15, 16, respectively, extend forwardly to spaced wings 17, which receive the shank 18 of a coupler between them. The wings are slotted and connected by a key 19 to the coupler shank and the ends of the key lie within slots in the sills 10, 11.

The new draft gear comprises a front follower assembly, which is of link form and consists of a rear follower block 21 connected along its top and bottom edges by longitudinal members 22 to a front end piece 23. The front end piece lies at the front end of the yoke adjacent the stops 12 and a follower block 24 is interposed between the end piece and the front end of the yoke and the stops. If desired, the end piece 23 and follower block 24 may be formed as a single element. The draft gear also includes a rear follower assembly or link 25, which consists of a rear follower block 26 connected along its opposite side edges by longitudinal members 27 to a front follower block 28. The links are interconnected, so that the front follower block 28 of the rear link extends through the front link and the rear follower block 21 of the front link extends through the rear link. The parts of each link are secured together by welding operations and the final welding operations are performed with the parts arranged to cause the links to be interconnected, as described.

The front end piece 23 and the rear follower block 21 of the front link are oblong and of the same height, which is slightly less than the distance between the inner faces of the longitudinal members of the yoke. The front end piece is, however, wider than the rear follower block and the end piece extends through the yoke with its vertical edges lying close to the inner faces of sills 10 and 11, while the rear follower block 21 has a width slightly less than the distance between the inner faces of the longitudinal members 27 of the rear link. The longitudinal members 22 of the front link have a width about equal to the width of the rear follower block 21 and thus the side edges of the member 22 are spaced inward from the side edges of the end piece 23. The rear follower block 26 of the rear link has a width approximately equal to the width of the draft pocket and a height slightly less than the distance between the longitudinal members of the yoke. The front follower block 28 of the rear link has a width the same as that of the rear follower block 26, but its height is less than that of follower 26 and slightly less than the distance between the longitudinal members 22 of the front link. The longitudinal members 27 of the rear link have a height equal to the height of the front follower 28 and substantially less than that of the rear follower 26. The sides of the front link and the top and bottom of the rear link are open and this facilitates the insertion of the cushioning elements in the links.

The front link 20 encloses a group of rubber springs, generally designated 29 and made up of individual springs 30 separated by sheet metal divider plates 31. The springs illustrated are of the type, which includes a sheet metal center plate having rings 32 of rubber disposed concentrically on opposite faces thereof and connected by plugs of rubber extending through openings in the plate. In the preferred arrangement, each of the rubber springs in the front group 29 has the same capacity and travel.

The rear link 25 contains a group of rubber springs, generally designated 33, with adjacent springs in the group separated by sheet metal divider plates. The springs in the group 33 include a sheet metal center plate 34, which is wider and not so high as the plates of springs 30, and each plate 34 carries two sets of concentric rubber rings 35 on each face, the rings of each set being concentric and aligned with those of a set on the opposite face. Aligned rings on opposite faces of the plate are connected

by plugs of rubber extending through openings in the plate. The springs in group 33 are all of the same capacity and travel and the two spring groups 29 and 33 also have the same capacity and travel. Preferably, each group contains the same number of springs and, although the springs in one group differ in construction from those of the other, all the springs employed in the gear have the same capacity and travel.

The groups of springs with their divider plates are inserted in their respective links with the links placed so that the rear follower block of the front link is in contact with the front follower block of the rear link. In this position of the parts, the overall length of the assembly from the outer face of the end piece 23 of the front link to the outer face of the rear follower block 26 of the rear link plus the thickness of the follower block 24 is somewhat greater than the specified length of an A. A. R. draft pocket. Accordingly, the link assembly is subjected to pressure to reduce its overall length to permit insertion of the assembly in a pocket and this causes the rear follower block 21 of the front link to be separated from the front follower block 28 of the rear link. With the pressure maintained, a wedge of wood or other suitable material is inserted between the two followers to hold them apart after the pressure is removed.

The link assembly can be shipped in compressed condition and it may be readily installed with its front follower 24 in a standard yoke. The yoke may then be moved up into the draft pocket from beneath, after which a carrier plate 36 is connected across the bottom flanges of the sills to support the yoke and the draft gear. Upon its installation, the gear and front follower 24 may not make tight contact with the front and rear stops or with the ends of the yoke, because of the wedge holding the spring groups compressed. However, after a short period of use of the gear, the wedge is crushed and the pieces fall out of the space between the followers.

In the operation of the draft gear described, the application of a force in buff through the coupler shank 18 to the front follower 24 causes the front link to move inwardly toward the rear stops 13. In such movement, the rear follower 21 of the front link compresses the rear spring group 33 against the rear follower 26, which is held stationary by the stops. At the same time, the front end piece 23 of the front link and the front follower 24 move inwardly and compress the springs of the front group 29 against the front follower 28 of the rear link, which is held stationary by the longitudinal members 27 connected at their rear ends to the rear follower 26. The two spring groups thus operate in parallel and, since both groups have the same capacity and travel, it will be apparent that the gear has the combined capacity of the two spring groups but the travel of only one.

Upon the application of a force in draft to the yoke, the rear end 14 of the yoke moves the rear follower 26 of the rear link away from the stops 13. The follower then applies pressure to the rear spring group 33 compressing it against the rear follower 21 of the front link, which is held stationary by the longitudinal members 22 engaging front end piece 23, which lies in contact with the front follower 24 held against movement by the front stops 12. The movement of rear follower 26 causes a corresponding movement of the front follower 28 of the rear link, which compresses the front spring group 29 against front end piece 23 and front follower 24.

The new gear has no moving parts generating significant friction and thus no parts are subject to wear. It may be readily made with a capacity of 30,000 ft.-lbs. and a travel in excess of the A. A. R. minimum. The gear never goes solid, as do ordinary friction gears, and

thus always provides a cushioning effect. However, its maximum travel under forces encountered in railway service is within the A. A. R. maximum.

I claim:

1. A draft gear, which comprises a front link consisting of front and rear end members of oblong shape, the members being of the same height and the front end member being wider than the rear end member, and longitudinal members of substantially the width of the rear end member of the rear link integrally connecting the end members along their top and bottom edges, a rear link interconnected with the front link and consisting of front and rear end members of oblong shape, the end members of the rear link being of the same width and the rear end member of the rear link being higher than the front end member of the rear link, and longitudinal members of substantially the height of the front end member of the rear link integrally connecting the end members of the rear link along their opposite side edges, the front end member of the rear link being wider than the rear end member of the front link and extending through the front link and lying in front of and adjacent to the rear end member of the front link, a group of rubber cushioning elements within the front link in engagement with the inner face of the front end member of the front link and the outer face of the front end member of the rear link, and a group of rubber cushioning elements within the rear link in engagement with the outer face of the rear end member of the front link and the inner face of the rear end member of the front link, the two groups of cushioning elements having the same capacity and travel.

2. A draft gear, which comprises a front link consisting of front and rear end members of oblong shape, the members being of the same height and the front end member being wider than the rear end member, and longitudinal members of substantially the width of the rear end member integrally connecting the end members along their top and bottom edges, a rear link interconnected with the front link and consisting of front and rear end members of oblong shape, the end members of the rear link being of the same width and the rear end member of the rear link being higher than the front end member of the rear link, and longitudinal members of substantially the height of the front end member of the rear link integrally connecting the end members of the rear link along their opposite side edges, the front end member of the rear link being wider than the rear member of the front link and extending through the front link and lying in front of and adjacent to the rear end member of the front link, a group of rubber cushioning elements within the front link in engagement with the inner face of the front end member of the rear link and the outer face of the front end member of the rear link, and a group of rubber cushioning elements within the rear link in engagement with the outer face of the rear end member of the front link and the inner face of the front end member of the rear link, all the cushioning elements in the group within the front link being alike in construction and all the cushioning elements in the group within the rear link being alike in construction and differing from the elements in the group within the front link, the two groups of cushioning elements having the same capacity and travel.
